TRAY BOX FOR SMALL BAKERY PRODUCTS

John W. Meinhardt and Dewey W. Tabor, Dallas, Tex., assignors, by mesne assignments, to Crown Zellerbach Corporation, San Francisco, Calif., a corporation of Nevada

Application May 25, 1955, Serial No. 511,068

1 Claim. (Cl. 229—27)

The invention relates to a container divided into a plurality of relatively shallow compartments by an automatically positioned longitudinal partition forming member.

More specifically, the invention provides a rigid container with opposed side walls and top and bottom panels, the interior thereof being divided into a plurality of shallow, superimposed compartments defined by an inner member folded to form one or more partitions extending at right angles to the side walls between the top and bottom panels of the container. For example, a two-compartment container may be formed from a one-piece paperboard blank scored, slotted and slit to form top and bottom panels and relatively narrow side walls and a partition member extending in an intermediate plane parallel to the top and bottom panels. The partition member is positioned as described by a longitudinal positioning panel co-extensive in length and integral with a side edge of the bottom panel, secured to the lower portion of one of the side walls, the positioning panel being of less width than the height of the side walls and integral with the side edge of the partition member. A partition connecting flange, also of less width than the height of the side wall, is hinged to the opposite side edge of the partition member and folded right angularly upward and secured in juxtaposed relation to the upper longitudinal portion of the other side wall. At this stage of the assembly, the container may be readily collapsed for shipment and storage. When it is opened up into rectangular form, the longitudinal positioning panel and partition connecting flange, which are secured to opposed side walls, serve to automatically position the partition in the desired intermediate plane parallel with respect to the top and bottom panels of the container. The partition member is provided with integral flaps at each end which are reversely folded inwardly and secured in reinforcing relation to the underface of the partition member, providing a smooth reinforcing fold at the end edges of the partition. Closure flaps are provided on each end of the top, bottom and side panels which fold inwardly and are secured together, serving to close the ends and further rigidize the entire structure. The described longitudinal positioning panel may obviously be integral with the top panel of the box and the partition member secured to the side walls by the positioning panel and connecting flange in the reverse relation from that described where the positioning panel is connected to the bottom panel of the box.

If desired, three or more superimposed compartments may be provided in the tray box by increasing the length of the one-piece blank sufficiently to provide two or more partition members connected together by longitudinal positioning panels similar to the positioning panel hereinbefore described.

An object of the invention is to provide a relatively shallow collapsible one-piece container with self-positioning longitudinal reinforcing partitions connected to opposed side walls extending in planes parallel to and

2

intermediate the top and bottom panel members, dividing the container into a plurality of spaced, superimposed compartments of substantially the same horizontal cross-section as the top and bottom panels, and flaps on the ends of the panel members and side walls, for closing the end and further rigidizing the container.

Another object is to provide a one-piece collapsible container with a dividing and reinforcing partition extending in a plane parallel to and intermediate the top and bottom panels, one side of the partition being secured to a side wall of the container by a relatively narrow panel integral with the side of one panel member and the adjacent side of the partition which automatically folds into juxtaposed relation with the upper margin of one side wall as the blank is opened up into rectangular form, while a connecting flange integral with the opposite side of the partition folds into juxtaposed position with the reverse margin of the other side wall, the combined width of the longitudinal panel and connecting flange being substantially equal to the width of each side wall, the end of the container being closed and rigidized by closure flaps on the ends of the top and bottom panels and side walls.

Still another object is to divide a relatively shallow one-piece container longitudinally into two compartments by a partition extending in a plane parallel to the top and bottom panel members of the container disposed intermediate therebetween, the outer portion of one side wall of the container being reinforced by a longitudinal positioning panel positioned in flatwise relation thereto, the panel being integral with the side of one panel member and the adjacent side of the partition, and the opposite portion of the opposite wall being reinforced by a connecting flange integral with the opposite adjacent side of the partition positioned in flatwise relation to the wall, the combined width of the longitudinal panels and the connecting flange being substantially equal to the width of the side walls, the ends of the container being closed by end marginal flaps on the panel members and side walls.

Other objects and advantages of this invention will be apparent to those skilled in the art upon a full and complete understanding of the construction and operation of this device.

The invention also consists in the parts and arrangements and combination of parts hereinafter described and claimed. The accompanying drawings form a part of this specification and like numerals and symbols therein appearing refer to like parts wherever they occur.

Fig. 1 shows a plan view of the blank from which a preferred form of the container is assembled;

Fig. 2 is a fragmentary plan view of the partition member with the reinforcing end flaps folded against the underface thereof;

Fig. 3 is a perspective view of the container in the process of folding showing the partition member in its spaced position prior to folding the top panel and its attached side wall;

Fig. 4 is a vertical section through the partially folded container blank of Fig. 3 taken in the direction of the arrows 4—4;

Fig. 5 is a perspective view showing the completion of the folding of the top panel and its attached side wall;

Fig. 6 is a vertical, sectional view of the folded structure of Fig. 5 taken in the direction of the arrows 6—6;

Fig. 7 is a perspective view of the completely assembled container;

Fig. 8 is a vertical, sectional view of the container of Fig. 7 taken in the direction of the arrows 8—8;

Fig. 9 is a plan view of a modified blank for assembling into a 3-compartment container; and

Fig. 10 is a vertical cross section of the container formed

from the blank shown in Fig. 9 taken in the same direction with respect to the structure as the arrows 8-8 of Fig. 7.

The blank A for forming a 2-compartment container is shown in Fig. 1. Parallel, longitudinal scores 20 and 21 define the end edges of the side walls 22-23, the top and bottom panels 24-25 respectively, partition member 27 and the ends of positioning panel 26 integrally connecting the partition member 27 to the bottom panel 25. The longitudinal scores also define the inner edges and fold lines of the side wall and closure flaps 28 and 29, and end closure flaps 30 and 31 integrally attached to the top and bottom panels 24 and 25 respectively, and the partition member reinforcing flaps 32. Transverse scores 33 define the side edges of the top panel 24 and the fold lines of side panels 22 and 23. The transverse scores 34 define the side edges of the bottom panel 25 and the second fold line of side panel 23 and the inner fold line of the positioning panel 26, while the transverse score 35 defines the inside edge of the partition member 27 and the outer fold line of positioning panel 26 while the transverse score 36 defines the outer side edge of member 27 and the fold line of the connecting flange 37. Slots 38 separate the side edges of the closure flaps 28, 29, 30 and 31.

The container may be conveniently assembled by folding the reinforcing flaps 32 flatwise against the under side of the partition panel 27 and securing them thereto by glue or other suitable means as shown in Fig. 2. The side wall 23 is folded upwardly in perpendicular relation to the bottom panel 25 and the partition member 27 is then superimposed over the bottom panel 25 with the connecting flange 37 secured in flatwise relation to the upper portion of the side wall 23. As a result of this folding, the positioning panel 26 will automatically become positioned right angularly upward from the bottom panel 25 and in parallel relation to the side wall 23. Fig. 3 illustrates this stage of the assembly. The top panel 24 is next folded over into parallel relation with the bottom panel 25 and the partition member 27 and the outer margin of the side wall 22 is secured in flatwise relation to the positioning panel 26. The perspective view of Fig. 5 shows the container in the stage of assembly just described. Flaps 28, 29, 30 and 31 are now folded inwardly and secured together to close the ends of the container and together with the partition member provide an exceptionally strong, rigid structure. The position of the several parts of the structure in the fully assembled form of the container are clearly illustrated in the vertical, sectional views of Figs. 6 and 8.

A modified form of the invention is illustrated in Figs. 9 and 10 wherein three superimposed compartments are formed within the container. The blank illustrated in Fig. 9 is similar to the two-compartment blank shown in Fig. 1 but has two-partition panels 40 and 41 with relatively narrow connecting panels 42, 43 and flange 44.

The modified form of the container may be assembled in a manner similar to the two-compartment form hereinbefore described. The reinforcing flaps 45 and 46 are folded flatwise against the under side of the partition panels 40 and 41 and secured by glue or other suitable means. The side wall 23' is folded in perpendicular relation to the bottom panel 25' as shown in Fig. 10 and the partition member 40 superimposed over and in parallel relation to the bottom panel 25' and the positioning panel 43 is secured to the side wall 23' at a position intermediate its width. The positioning panel 42 is next secured to the outer portion of the side wall 22'. The partition member 41 is then reversely folded parallel to partition 40 and top and bottom panels 24 and 25 and the connecting

flange 44 is secured to the inner portion of the side wall 22', completing the assembly of the three-compartment container. The ends of the container are closed hereinbefore described by folding and securing the closure flaps 28', 29', 30' and 31' in overlapping relation.

The compartmented container of the invention is especially adapted for packing, shipping and storing relatively small and fragile bakery products and other fragile articles. Small bakery products, as distinguished from 10 loaves of bread, for example, are quite easily damaged and must be packed in a single layer for transporting and delivering to the retail markets. The subject invention provides a thoroughly reinforced container, resistant to all stresses incident to normal handling and transportation.

15 It is to be understood that the embodiments herein described are illustrative and not restrictive, and it is also to be understood that the invention may be susceptible of embodiment in other modified forms and that all such modifications which are similar or equivalent hereto come 20 equally within the scope of the claim next appearing.

What we claim is:

A one-piece paperboard box for bakery products and the like having top and bottom walls and front and back walls and open ends closeable by closure flaps integral 25 with the top, bottom, front and back walls, at least one substantially flat partition dividing the box into upper and lower compartments, the partition member having one of its marginal portions upturned at substantially a right angle thereto and constituting a connecting flange of less 30 height than the back wall which is integral with the bottom at a fold line, the flange being in engagement with the back wall and permanently secured to an inside upper portion thereof, the opposite marginal portion of the partition being downturned at substantially a right angle 35 thereto and constituting a front positioning panel and with its lower edge integral at another fold line with the bottom wall, reinforcing flaps constituting the other opposed marginal portions of the partition reversely folded and secured in engagement with adjacent portions of the partition, 40 the length of the reinforcing flaps being substantially the width of the partition and the width of the flaps being considerably less than the length of the partition, the top wall being of substantially the same dimensions as the partition and bottom wall and extending from and integral 45 with the hinge line at the top of the rear wall and having a closure flap at each side thereof and having a free edge, a front wall panel projecting from the free edge and the dimensions thereof being substantially the dimensions of the rear wall, whereby the container is collapsible along 50 the said fold lines into substantially flat condition for shipment and storage purposes, when erected for use the lower portion of the front wall is parallel with, overlaps and is permanently secured to the positioning panel with the top wall permanently closing the top of the container and thus 55 forming the upper compartment in superposed parallel relation with the lower compartment, the ends of the container being open whereby pastry or the like may be inserted into or removed from either compartment, and the closure 60 flaps being adapted for closing the respective ends of the box.
